UNITED STATES PATENT OFFICE.

WILLIAM H. JAMOUNEAU, OF NEWARK, NEW JERSEY.

DESIGN FOR A SPOON, &c.

SPECIFICATION forming part of Design No. 20,943, dated July 14, 1891.

Application filed May 9, 1891. Serial No. 392,248. Term of patent 7 years.

To all whom it may concern:

Be it known that I, WILLIAM H. JAMOUNEAU, a citizen of the United States, residing at Newark, in the county of Essex and State 5 of New Jersey, have invented and produced a new and original Design for Handles for Spoons, Forks, and other Articles technically termed in the trade as "Flat Ware;" and I do hereby declare the following to be a full, clear, 10 and exact description of the invention, such as will enable others skilled in the art to which it appertains to make and use the same, reference being had to the accompanying drawings, and to letters of reference marked thereon, 15 which form a part of this specification.

The figure of the drawing is a front plan of a spoon of my improved design, of which the following is a specification, the one figure being deemed sufficient to fully illustrate the 20 same.

The leading feature of the design consists in the handle of the spoon or fork, which is of a shape at the upper extremity thereof closely resembling the head and bust of Washington as presented in Houdon's mask, the 25 outline of the head corresponding with the outline of the handle.

In said drawing, *a* indicates the bowl of the spoon, *b* the shank thereof, and *c* the broadened extremity of the handle, which has the 30 outline of a man's head and the upper part of his bust, the same resembling the head and bust of Washington. The lateral outline of the head corresponds or coincides with the lateral edge or outline of the extremity of the 35 handle. Below the bust the handle of the spoon gradually tapers toward the bowl of the spoon, and on the face of the contracting part is the word ornament "Washington," which, however, forms no part of my design 40 and may be omitted.

What I claim as new is—

The design for a spoon or fork handle herein shown and described.

In testimony that I claim the foregoing I 45 have hereunto set my hand this 7th day of May, 1891.

WILLIAM H. JAMOUNEAU.
